United States Patent Office

Des. 183,608

Patented Sept. 30, 1958

183,608

HANDLE, OR SIMILAR ARTICLE

Meyer Greitzer, Los Angeles, Calif.

Application October 21, 1957, Serial No. 48,170

Term of patent 7 years

(Cl. D10—8)

Fig. 1.

Fig. 2.

Fig. 3.

Fig. 2 is a side elevational view thereof;

Fig. 3 is an end elevational view thereof.

The stippled area shown in Figs. 1 and 3 designates a color contrasting with the color of the remainder of the handle.

I claim:

The ornamental design for a handle, or similar article, substantially as shown and described.
